UNITED STATES PATENT OFFICE.

VICTOR W. HELANDER, OF SAN PEDRO, CALIFORNIA.

SIPHON PUMP.

Application filed November 2, 1925. Serial No. 66,407.

To all whom it may concern:

Be it known that I, VICTOR W. HELANDER, a citizen of the United States, and a resident of San Pedro, in the county of Los Angeles and State of California, have invented certain new and useful Improvements in Siphon Pumps, of which the following is a specification.

My invention relates to pumps for siphoning liquids from a receptacle, and a purpose of my invention is the provision of an extremely simple, durable and effective pump which is manually operable to create siphonic flow of a liquid from a receptacle and in such manner that the siphon can be broken and renewed at the will of the operator, thereby providing complete control of the exhaust of the liquid from the receptacle.

I will describe only two forms of siphon pumps embodying my invention, and will then point out the novel features thereof in claims.

In the accompanying drawings—

Figure 1 is a view showing in vertical longitudinal section one form of siphon pump embodying my invention, with the parts thereof in position for exhausting the air from the barrel of the pump;

Figure 2 is a view similar to Figure 1, showing the parts of the pump in position for drawing a liquid into the barrel to initiate the siphonic flow of liquid through the pump;

Figure 3 is a vertical sectional view taken on the line 3—3 of Figure 1;

Figure 4 is a a detail perspective view of the outlet valve embodied in the pump shown in the preceding views;

Figure 5 is a horizontal sectional view taken on the line 5—5 of Figure 1;

Figure 6 is a fragmentary vertical sectional view showing a modified form of siphon pump embodying my invention.

Similar reference characters refer to similar parts in each of the several views of the drawing.

Referring specifically to the drawings, my invention in its embodiment as shown in Figures 1 and 2 comprises a barrel 15, the lower end of which is interiorly threaded to receive a plug 16 having a bore 17 normally closed at its upper end by a flap valve 18 which is movable inwardly to an open position, as illustrated in Figure 2, such open position being defined by a cage 19 secured

to the plug 16. The plug 16 is shouldered as indicated at 20 to limit its inward securing movement, and the lower end of the bore 17 is enlarged and its walls screw threaded 60 to receive an exteriorly threaded collar 21 having a flange 22 to which is secured a cup shaped filtering member 23.

Adjacent the upper end of the barrel 15 a discharge spout 24 is formed integral with the barrel and laterally disposed, with its outer end constructed to provide an inclined valve seat 25 against which an outlet valve 26 normally rests to close the nozzle. As shown in Figure 4, this valve 26 is in the 70 form of an ovate disk, with the ends thereof provided with recesses 27 which, as shown in Figure 3, loosely receive a cage 28 in such manner that the cage functions to support the valve for movement to open and closed 75 positions, and because of the inclination of the valve seat 28 the valve normally gravitates to closed position. The cage 28 is secured at its ends to the nozzle 24, and a portion of the nozzle is exteriorly threaded to 80 receive a cup shaped connector 29 provided with a tubular expansion 30 exteriorly corrugated to receive one end of a flexible tube 31.

In the upper end of the barrel 15 is secured a broad plug 32 having a tubular extension 33 exteriorly corrugated to receive a bulb 34 formed of rubber or other suitable material, while adjacent the plug 32 the barrel is formed with a tubular extension 35 90 shaped at its point of connection with the barrel to provide a conical seat 36 normally engaged by a conical valve 37 provided with a stem 38, to the outer end of which is keyed a knurled head 39. A spring 40 is interposed between the valve 37 and the head 39 for normally urging the valve to closed 95 position, and it will be understood that by pushing the valve head inwardly against the tension of the spring 40 the valve 37 will be opened. In the open position of the valve atmospheric air is supplied to the barrel through a port 41 in the tubular extension 35.

In operation, the filtering cup is adapted 105 to be submerged in the liquid to be elevated, the filtering cup serving to strain the liquid and prevent entrance of solid particles into the barrel. With the cup submerged, the bulb 34 is squeezed to the contracted position shown in Figure 1, thereby placing the air in the barrel under pressure to maintain the 110

inlet valve 18 closed but to open the outlet valve 26, thereby permitting the air to be exhausted from the barrel into the tube 31. Upon release of the bulb 34 it returns to its 5 normal expanded position as shown in Figure 2, and in so doing creates a negative pressure in the barrel 15 to close the outlet valve 26 and open the inlet valve 18, thus drawing liquid into the barrel and thereby 10 setting up the siphonic action to cause the liquid to continuously flow into the barrel through the lower end thereof and outwardly of the barrel through the nozzle 24, it being understood that the force of the liquid 15 will operate to open the outlet valve 26 so that the liquid can be discharged into the tube 31. With this siphonic action once established it will be understood that the liquid will continue to flow through the 20 pump until the siphon is broken. The siphon may be broken by opening the valve 37 to admit atmospheric air to the barrel as has been described. In this manner any amount of liquid can be discharged from the 25 receptacle and the flow of the liquid terminated at the will of the operator through the manipulation of the valve 37.

Referring now to Figure 6, I have here 30 shown the upper end of the barrel 15 provided with a cap 42 upon which is slidably mounted the rod 43 of a plunger 44 reciprocable in the barrel by reciprocating the rod through a handle 45. The plunger 44 is adapted to take the place of the bulb 34 to 35 create a negative pressure in the barrel 15, and the plunger is particularly designed for use in relatively large siphon pumps where a relatively high negative pressure is necessary to initiate the siphonic flow of the 40 liquid.

Although I have herein shown and 45 described only two forms of siphon pump each embodying my invention, it will be understood that various changes and modifications may be made herein without departing from the spirit of the invention and within the spirit and scope of the appended claims.

I claim:

1. A siphon pump comprising a barrel, a

50 plug in the lower end of the barrel having a bore constituting a liquid inlet for the barrel, a flap valve normally closing the inlet and opening inwardly, a cage secured to the plug for defining the open position of the valve, a filtering element detachably secured to the plug, a nozzle extending laterally from the barrel and having an inclined valve seat, a cage secured to the nozzle, an oval shaped flap valve movable on the cage and normally engaging the seat to close the 60 nozzle, said valve provided with notches loosely receiving the valve cage, a connector for housing the second valve and cage and detachably associated with the nozzle, a tubular extension on the barrel provided with an air inlet port, a valve disposed in the extension for controlling said port and normally urged to closed position, a plug disposed in the upper end of the barrel and having a tubular extension and formed with a bore communicating with the barrel, and a manually operable element connected to the extension for creating a negative pressure in the barrel.

75 2. A siphon pump comprising a barrel, a plug in the lower end of the barrel having a bore constituting a liquid inlet for the barrel, a flap valve normally closing the inlet and opening inwardly, a cage secured to the plug for defining the open position of the valve, an outlet nozzle extending laterally from the barrel and having an inclined seat, a flap valve normally engaging the nozzle seat normally closing the outlet nozzle and opening outwardly, a cage secured to the nozzle for defining the open position of the said valve, a tubular extension on the barrel provided with an air inlet port, a plunger valve disposed in the extension for controlling said port and normally urged to closed position, a plug in the upper end of the barrel having a bore communicating therewith, an extension on the plug, and a manually operable element connected to the plug extension for creating a negative pressure in 85 the barrel.

VICTOR W. HELANDER.
